Jeremiah Fiske
Letters Patent. Patent No. 9. 1833. Sept.

The Schedule referred to in these Letters Patent, and making part of the same, containing a description in the words of the said Jeremiah Fiske himself of his improvements in the Threshing Machine.

To all to whom these presents shall come. Be it known that I, Jeremiah Fiske, of Weld, in the county of Oxford & State of Maine, have invented a new and useful machine for threshing wheat and other grain from straw, for threshing hard grass seed from straw, & for separating clover seed from the chaff or hull & also for threshing oats from the straw & separating it from the hull; & that the following is a full & exact description of the construction and operation of the said machine, as invented & improved by me.

The principle of this improved & useful machine, consists in having a cylinder, say about two feet six inches in diameter and eight feet long, covered with sheet iron, perforated so as to render the external surface completely rough like a grater. This cylinder lies horizontally, and is made of wood, except the sheet iron covering and may be solid. In the centre of each end, is an iron or steel wedge or pin, on which the cylinder revolves, presenting the rough surface of the sheet iron to a curved bed constantly. This curved bed is situated obliquely backwards of the cylinder, the upper part of it being called the regulator extending to the centre of the cylinder superiorly. It is made of good substantial wood, should be about two inches in thickness, and is length equal to that of the cylinder. The curvature of this bed is such, that when properly applied to the cylinder, there shall exist a uniform space between them of about one fourth of an inch; and will enclose about one half of the circumference of the cylinder. This curved bed is supported at the ends by two plates. Through each of these

planks are two holes near the ends made large enough to admit screws with large shoulders, the holes being large enough to admit a little play or movement when the screw is turned a little back.

The superior or upper screw in each plank enters a top rail or cap piece in the frame (in which the cylinder moves), above the cylinder; while each of the inferior or lower screws enters a middle sheet fast below. By this arrangement the lid piece may be approached nearer to, or further receded from the cylinder at pleasure. The concave surface of this lid piece is covered with perforated sheet iron rendered greater like, so that the concave surface of the lid piece shall correspond to the convex surface of the cylinder - for many hours. The upper part of this covered lid piece, called the regulator is six or seven inches, in width, detached from the other broad part of the lid and joined only by the sheet iron, which also covers the inner surface of this, and serves also as a hinge on which the regulator turns; so that this regulator may be raised or depressed, enlarging or lessening the space between it and the cylinder, to admit more or less feed at pleasure, hence it is called the regulator. On the external side some handles or bars may be attached, so as to graduate to its elevation or depression.

Above the cylinder, and over the side opposite to the covered lid, is a slide or hopper made in the form of a plane inclined towards the cylinder, with side pieces, to prevent the grain from falling off, presenting the grain, stored up to greater depth of the cylinder, as fast as admitted by the regulator. This slide is about $\frac{1}{2}$ in. fast six inches in length, in width, equal to the length of the cylinder. One of the pins on which this cylinder revolves, serves as an axle to a wheel fastened on the out end, to which the power ^{is} communicated to move the cylinder, that $\dots$ of the cylinder is always approaching the covered lid above, and receding below.

This machine may be put in operation by means

of hand, horse, steam or water power, and the dimensions of each part diminished or enlarged accordingly.

This cylinder being put in rapid motion as above described, the grain or other material to be threshed or hulled, is placed on the slides, and thrown forward to the rough surface of the cylinder, and carried thence by the motion between the opposing surfaces of the cylinder and the curved bed which completely ends ... the hull & separates the grain or seed from it. In separating rice & smaller seeds from the hull it may be necessary to apply the curved bed nearer the cylinder than when threshing from the stalk. This is done by means of the scree with large shoulders as before described. A wooden frame is to be constructed of joists or strong timbers, of dimensions adapted to the size and bigness of the cylinder & curved bed; with gates supported by two short posts for the pins in each end of the cylinder to hang or play on. Dated at Wethersfield this sixth day of April anno Domini 1833.
